UNITED STATES PATENT OFFICE.

NICHOLAS SMIRNOFF, OF BROOKLYN, NEW YORK.

ROCKING AND GALLOPING HORSE.

Application filed June 13, 1927. Serial No. 198,529.

This invention relates to rocking horses and in particular to one adapted to be used by a child in play.

The most important object of the invention is to provide a rocking horse which, while capable of a rocking motion will also have an advance or travel motion.

A further object of the invention is to provide a device of this character which will be simple in construction and parts of which will operate to advance the rocking horse with a predetermined speed and without jar or jerking operation of its parts.

A further particular object of the invention is the provision of a rocking horse, the rockers of which are so curved that they can inter-work during their swinging movement to steadily advance the horse during a rocking motion thereof.

To enable others skilled in the art to fully comprehend the underlying features of my invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a view in sectional elevation of a rocking horse constructed in accordance with my invention, the same being shown partly in section to illustrate the inner parts thereof and the position of the rocking members being so illustrated that they show that the figure is about to take an advance movement.

Figure 2 is a view similar to Figure 1 showing how the construction of the rocking horse would appear after it is rocked forward on the front rocker and the horse rotates about its pivot point to bring the rear rocker forward.

Figure 3 is a view in rear sectional elevation taken on the line 3—3 of Figure 1, the view illustrating the relative positions of the rockers and their operating elements.

Referring to the drawings in detail, 1 indicates the hollow body of a rocking horse which is preferably formed of two symmetrical halves of moulded material, such as fibre, shaped to form the horse body and arranged to receive the rear rocker or main frame 2, which consists of the suitable frame pieces 2^a joined at their corners by the corner plates 2^b, the diagonally disposed plates being joined by the brace piece 2^c and other

suitable tie rods, the extended portions 2^d of the rear rocker frame is joined through the medium of a suitable reinforce plate 2^e to the rear rocker pieces 3, these rocker frames 2 being disposed at both sides of the body of the animal and being joined by the various tie rods 7 and 9 and the pivot rod 4, there being also provided at the front end of the frame pieces 2 and extending transversely of the horse to connect the front end of the frame pieces, the cross piece 22, the purpose of which will be hereinafter described. The ends of the pivot rod 4 are secured in the frame pieces 2 and are arranged to provide an axle or pivot on which the front rocker frame swings, the front rocker frame consisting of the bell crank shaped members 5 which are suitably joined through the medium of plates 5^a to the rockers 6, there being one of each of the front rocker frame pieces 5 at each side of the body of the horse and adjacent the main frame pieces 2 but inside thereof, so that the rockers 6 swing inside the rear rockers 3, the bell crank members 5 are joined by the tie rods 11, 12, 13, 16, and 27, while the rockers 6 are joined by the tie rods 14 and 15 and the rockers 3 are joined by the tie rods 10 and 29, the lower extensions of the frame pieces 2 being also joined by the tie rod 8 to which is secured one end of a tension spring 23, the opposite end of the spring being secured to the tie rod 11 which connects the free end of the bell crank rocker member 5. The tie rod 12 has pivoted there-to intermediate its ends, the latch 20, the extended portion 20^a of which is adapted to contact with and be limited in its movement by the tie rod 16, which will be later explained. The end 20^a of the latch 20 is urged against the tie rod 16 through the medium of the spring 24 which is secured at its opposite end to the tie rod 13.

I am quite aware that patents have been obtained upon rocking horses which are adapted to travel longitudinally but one of the large problems in making a successful device of this character has been not only the proper curvature of the rockers but has been the arrangement of parts to give the necessary advance movement without interfering with the rocking motion of the horse. I have overcome these problems by providing on the pivot rod 4, a suitable pendulum 18 which is secured to the lower end of the rigid rod 17 which is connected to the sleeve

17^a, this sleeve being freely fitted over the rod 4 so that it can revolve therearound and at substantially right angles to the rod or pendulum holding lever 17, I provide a pendulum arm 17^b which overlies the latch 20 and is connected thereto through the medium of a flexible member 19 such as a string, cord or chain.

It is quite evident, from reference to Figure 1 that when the horse is occupied and is being rocked that at the moment of rocking ahead from the position shown in Figure 1, the pendulum 18 will remain in its vertical position revolving on the pivot rod 4 thereby causing the pendulum arm 17^b to pull on the string 19 by the progressive rocking in a forward direction. This pull overpowers the action of the spring 24 and lifts the hook or latch 20 free from its latched position in connection with the latch plate 21 which is suitably positioned on the cross bar 22 in position to be engaged by the latch. When the latch has been disconnected, the forward frame pieces or bell crank shaped members 5 will of course be disconnected from the cross bar 22. It will be noted that while this connection existed, the whole structure rocked without changing the relative position or arrangement of its parts with the exception of the pendulum, which of course, is hung vertically at all times, but after the disconnection of the latch, the body of the horse under weight of the rider turns about the pivot rod 4. This will be evident from inspection of Figure 2 wherein is shown the position assumed after rotation has been accomplished and at the moment of starting the backward rocking motion.

It is not necessary to go into the mathematical computations of the curves of the rockers as they have been especially designed to enable the continued rocking motion of the horse. It is sufficient to say that this special construction of the curves of the rocker are so shaped that the end of rotation places the curves C—D below the curve N—B, thereby allowing the rearward rocking motion to take place only on the rockers 3, which of course allows the bell crank shaped members 5 under action of the spring 23 to be immediately restored to their former position as shown in Figure 1. It is of course evident that the spring 23, while in rotation, is drawn out as shown in Figure 2 and its tension gradually increasing, provides a great degree of elasticity to the rotation of the horse.

From the moment of starting the rearward rocking motion, rockers 6 are raised from the ground and the contraction of the spring 23 turns the levers 5 about the pivot rod 4 until they abut against the cross bar 22. When this occurs, the hook 20 or latch slides over the latch plate 21 and falls over the edge thereof, making under the pull of

the spring 24, a positive connection between the lever 5 and the cross bar 22. Due to this action, as described, the horse will advance after each rocking motion back and forth, a distance corresponding to the length of the curve N—B which represents the tread of the galloping horse.

It is quite evident that by changing the length of the string 19 or the point of its connection to the pendulum arm 17—B, I can change the starting moment of rotation and can thereby control the distance of travel of the rockers with each rocking movement. In order to stop the free swinging movement of the pendulum to convert the galloping horse into a plain rocking horse, I have provided an eye 26 on the rear face of the pendulum 18 and in alignment therewith but positioned pivotally on the tie bar 9, I have provided the hook 25 which is arranged to engage the eye 26 to maintain the pendulum 18 at a certain position so that advance of the horse will not take place during a rocking movement. The forward rockers 6 are joined together by the tie rods 14 and 15 and it is quite evident that they do not interfere with the rotating motion of the horse because the rockers 6 are disposed inwardly of the rockers 3.

The position of the pivot rod 4 or the center of rotation is determined in a practical way so that the best balancing conditions of the whole structure are obtained but in any case, it must be nearer to the neck of the horse and approximately as shown in the figures of the drawing.

The moulded fibre body which may include a moulded saddle, is secured to the frame pieces 2 in any manner, such for instance, as by screws, bolts, or the like and the moulded hind legs of the body are in like manner secured to the lower extensions 2^d of the rocking frames 2.

It is quite evident, therefore, that I have provided a rocking horse of simplified construction which, due to the operation of its pendulum and pendulum operated hook, first holds the body as a unitary structure and then releases part thereof so that there is a relative movement between the parts so that upon subsequent rotating motion, travel is obtained without in any way disturbing the rocking motion of the horse.

It is also evident that I have provided a successfully operated rocking and galloping horse which has few parts, will not get out of order and which will afford amusement to children by providing not only the usual rocking motion but also one in longitudinal direction and the speed of travel will of course depend upon the speed with which the horse is rocked.

While I have illustrated and described my invention with some degree of particularity, I realize that in practice various alterations

therein may be made. I therefore reserve the right and privilege of changing the form of the details of construction or otherwise altering the arrangement of the correlated parts without departing from the spirit of the invention or the scope of the appended claims.

Having thus described my invention what I claim as new and desire to secure by 10 United States Letters Patent is:—

1. A rocking horse comprising a body, a main rocker frame secured thereto, an auxiliary rocker frame pivoted to the main frame, a latch on the auxiliary frame for 15 connecting the same to the main frame, a pendulum, a connection between the pendulum and the latch whereby during the rocking motion, the pendulum will release the latch to disconnect the frame and said pivot point being located so that after release of the latch, the frame will swing forward about the pivot point and relatively to said auxiliary frame to cause advance movement of said horse.
2. A rocking horse comprising a body, a main rocker frame secured thereto, an auxiliary rocking frame pivoted to the main frame, a latch on the auxiliary frame for 20 connecting the same to the main frame, a pendulum, a connection between the pendulum and the latch whereby during a rocking motion the pendulum will release the latch to disconnect the frame, said pivot point being located so that after release of the

latch, the main frame will swing forward 35 about the pivot point and relatively to said auxiliary frame to cause advance movement of said horse and a member arranged to be placed under tension upon a swinging movement of said main frame and adapted to 40 subsequently swing the auxiliary frame into position to be latched to said main frame.

3. A rocking horse comprising a body, a main rocker frame, an auxiliary rocker frame pivoted thereto, a latch carried by one 45 of said frames and arranged to releasably secure the frames together, and a pendulum connected to said latch and arranged to release the frames at a predetermined point in the rocking motion so that longitudinal 50 movement of the rocking horse is caused.

4. A rocking horse comprising a body, a main rocker frame secured thereto, an auxiliary rocker frame pivoted to the main frame, a latch carried by the auxiliary frame 55 for detachably joining both the frames together, a pendulum, a flexible connection between the pendulum and the latch for causing release of the latch whereby the main frame will have movement relative to the auxiliary frame to cause a longitudinal 60 movement of the horse during rocking motion thereof and means for holding said pendulum whereby the connecting member is held flexible and release of the latch is prevented.

In testimony whereof I affix my signature.
NICHOLAS SMIRNOFF. [L.S.]
